UNITED STATES PATENT OFFICE.

JAMES R. PEARSON, OF CINCINNATI, OHIO, ASSIGNEE TO THE ACME MACHINE TOOL COMPANY, OF CINCINNATI, OHIO, A CORPORATION OF OHIO.

BELT-SHIFTER.

1,104,218.

Specification of Letters Patent. Patented July 21, 1914.

Application filed February 26, 1914. Serial No. 821,159.

To all whom it may concern:

Be it known that I, JAMES R. PEARSON, a citizen of the United States, residing at Cincinnati, Ohio, have invented a new and 5 useful Improvement in Belt-Shifters, of which the following is a specification.

My invention relates to belt shifters of the class adapted to the use of stepped pulleys or for other suitable purposes, and the 10 objects of my improvements are to provide means for shifting the opposite stretches of the belt alternately; to provide pawl and ratchet mechanism for turning two shafts alternately in opposite directions; to provide 15 means for reversing the alternate direction of the shafts; to provide a hand lever with double and reversible pawl and ratchet mechanism, and to provide simple and durable construction and assemblage 20 of the various members for securing facility of operation and efficiency of action. These objects may be attained in the following described manner as illustrated in the accompanying drawings, in which:—

25 Figure 1 is a front elevation of a belt shifter embodying my improvements; Fig. 2 a side elevation; Fig. 3 a front elevation of the pawl and ratchet connections for actuating shafts disposed in alinement; 30 Fig. 4 a section on the line *b* . . . *b* of Fig. 6; Figs. 5 and 6 cross sections on the line *a* . . . *a* of Fig. 4 looking toward the right and left respectively, and Fig. 7 a plan of a shifter rack and pinion.

35 In the drawings 1 and 2 represent stepped pulleys, 3 the belt therefor, 4 and 5 shifter racks provided with loops 6 and 7 for the respective stretches of the belt. Bracket housings 8 and 9 are formed with 40 guides 11 for the longitudinal movement of the racks therethrough.

Shafts 12 and 13 in alinement are journaled at opposite ends in the housings 8 and 9 and each provided with a pinion 14 45 in engagement with the corresponding rack. Said shafts are journaled at their adjacent ends in a housing 15 and provided with corresponding ratchet wheels 16 and 17. A housing 18 swiveled on the shafts within 50 the slot 19 formed in housing 15 is provided with a double set 21 and 22 of oppositely disposed pawls which are pivotally secured in the recesses 23 and 24 formed therein. Springs 25 serve to move and maintain the 55 pawls under a yielding pressure in engage-

ment with the corresponding ratchet wheels. A hand lever 26 swiveled on the stud 27 formed on the housing 18 is formed with an annular flange 28 having a double set 29 and 31 of internally projecting bosses formed thereon. A radial pin 32 secured in the stud 27 movably engages with the slot 33 formed in the hand lever for limiting its rotative movement. 60

In operation, the hand lever may be 65 turned in one direction to the extent of the slot therein for actuating the bosses 29 to move and maintain the pawls 21 out of engagement with the ratchet wheels and also for disengaging the bosses 31 from the pawls 22 that the springs 25 may move them into engagement with the corresponding ratchet wheels. The opposite turn of the hand lever actuates the corresponding bosses in like manner to disengage the pawls 22 and 70 permit the automatic engagement of the pawls 21 with the corresponding ratchet wheels. The lateral movement of the hand lever alternately in opposite directions during the engagement of pawls 21 serves to 75 turn the shafts with the pinions alternately in opposite directions for moving the racks with the corresponding stretches of the belt alternately on adjacent steps of the pulleys and toward one end thereof. In like manner, during the engagement of pawls 22 the 80 same lateral movements of the lever serve to actuate the same connections to shift the corresponding stretches of the belt alternately on adjacent steps of the pulleys and 85 toward the opposite end thereof. 90

Having fully described my improvements, what I claim as my invention and desire to secure by Letters Patent of the United States is:—

95 1. A belt shifter comprising two shafts provided with ratchet wheels, a housing swiveled thereon and provided with pawls arranged to engage with the said wheels, and a hand lever provided with selective means for disengaging certain of said pawls from the wheels. 100

105 2. A belt shifter comprising two shafts journaled in a housing and provided with adjacent ratchet wheels, a hand lever swiveled concentric with the wheels and provided with a plurality of pawls adapted to engage with the wheels, and selective means actuated by said lever for engaging or releasing the pawls in pairs and for turn- 110

ing the shafts alternately in either of opposite directions.

3. A belt shifter comprising a housing, two shafts in alinement with their adjacent ends journaled therein and each provided with a ratchet wheel, a member swiveled concentric with said wheels and provided with two pairs of pawls adapted to engage with opposite sides of the corresponding wheels, and a hand lever swiveled on the member and provided with selective means for alternately disengaging certain of said pawls.

4. A belt shifter comprising oppositely

disposed shafts, a ratchet wheel and a pinion secured on each shaft, shifter racks engaging with the pinions, pawls arranged to engage with the wheels, a hand lever and selective means controlled thereby for alternately disengaging certain pawls, whereby the shafts may be turned alternately in either of opposite directions and in pre-determined order.

JAMES R. PEARSON.
